UNITED STATES PATENT OFFICE

FRANCIS OLIVIAUX, OF PARIS, FRANCE

DISTRIBUTING APPARATUS FOR CIGARETTES AND OTHER ARTICLES

Application filed April 30, 1927, Serial No. 187,901, and in France May 26, 1926.

This invention relates to a distributing apparatus for cigarettes and other articles such as cigars, matches and the like.

The said distributing apparatus, which 5 comprises a suitable recipient and a cover which is pivotally mounted on the orifice or mouth of the said recipient by suitable means, for instance by a hinge, is characterized by the fact that the said cover is connected by suitable intermediate elements with a bottom part or holder which is slidable in the said recipient and serves to support the cigarettes, cigars, matches or the like which are placed on end, the several parts being so combined 10 that when the cover is raised to open the apparatus, this will cause the said movable bottom to slide towards the mouth of the said recipient, so that the cigarettes, cigars, matches or the like will project from the 15 recipient upon a length which will enable them to be readily seized. When the cover is lowered to close the recipient, the said movable bottom part or holder will slide towards the lower end of the apparatus, thus 20 withdrawing into the said recipient the cigarettes, cigars, matches or the like which rest upon the said movable bottom or holder.

The invention further comprises the following additional features which may be 25 variously combined with the principal characteristic.

At the upper part of said recipient are disposed one or more chambers, above the said movable holder; said chambers may have a 30 sufficient size to contain a certain number of articles to be distributed, either in packages or in the loose state, or the chambers may be of small size in order to form individual recesses each containing a single object.

40 A spring is suitably combined with the intermediate devices connecting the cover with the movable bottom or holder, and the said spring urges the said devices in the proper direction for opening the cover and sliding 45 the said holder towards the mouth of the recipient.

A spring is suitably combined with the movable bottom or holder, and it urges the said holder in the suitable direction for the 50 sliding of the holder towards the mouth of

the recipient and for the opening of said cover.

A closing device with catch release is combined with the recipient and its cover. A second distributor in accordance with 55 the invention, and of smaller size, is combined with the said movable holder, in such manner that it may be withdrawn into the recipient together with the objects to be distributed, or may be extended together with such objects; 60 for example, this second distributor may contain matches, whilst the main distributor contains cigars or cigarettes.

The said invention is further characterized by the general dispositions and the details of 65 the apparatus, of which various constructional forms are hereinafter described with reference to the appended drawings, which are not of a limitative nature.

Fig. 1 is an axial section of a cigarette distributor of round shape, in the open position. 70

Fig. 2 is an analogous view of the same distributor in the closed position.

Fig. 3 is a plan view corresponding to 75 Fig. 1.

Fig. 4 is a horizontal section on the line X—X of Fig. 2.

Fig. 5 is a lateral section on a middle plane Y—Y of Fig. 7, showing a distributor of 80 rectangular shape, in the open position, containing a match distributor which is also in the open position.

Fig. 6 shows the same apparatus with both 85 distributors closed.

Fig. 7 is a plan view corresponding to 85 Fig. 5.

Fig. 8 is an elevational view of a section on a middle plane, showing a distributor provided with recesses and without a spring.

Fig. 9 is a plan view, with the cover removed, of a distributor without individual recesses. 90

Fig. 10 is an elevational view, in section, of a match distributor provided with recesses but without a raising spring. 95

Fig. 11 is a plan view, with the cover removed, of a distributor without recesses, which is divided into three chambers.

In the first form of construction, the cigarettes are placed vertically in the recesses 1 100

and are supported by a sliding plate 2 carried by a lever 3 having in its upper end an aperture 4 in which is slidable the pin 5 which is mounted in a forked bracket 5^a secured to the bottom plate 2. The lever 3 is pivotally mounted at 6 at the lower part of the distributing device and is urged by a spring 7 which tends to pivot it upwardly. The bell-crank lever 8 is pivoted at its lower part at 9 to the lever 3, and is pivotally mounted at its upper part at 10 upon a forked bracket 10^a secured to the cover 10 of the apparatus.

The operation is as follows, with reference to Figs. 1 and 2. By pushing the button 11, the edge 12 of the cover will be released from its retaining hook 13; the lever 3 rises under the action of the spring 7, pivoting on the axle 6. The plate 2 will thus be raised, and the cover 16 will pivot on its hinge under the action of the lever 8.

In the construction shown in Figs. 5, 6 and 7, the general functioning of the apparatus is quite the same as before, but a match-distributing device 14 is secured to the plate 2 of the cigarette apparatus, and this device will be raised at the same time as the cigarettes. In the said distributor, the matches are placed vertically in suitable recesses and are raised, when the cover is opened, by means resembling those employed in the cigarette distributor. In the construction herein represented, the spring 7 is replaced by a spiral spring 17 surrounding a rod 17^a which is secured to the stationary part of the distributor 14 and on which is slidable the bottom plate 22. The arm 18, analogous to the arm 8, is secured directly to the movable plate 22.

In the two modifications which are shown in Figs. 8 and 10 and are in general constructed respectively as shown in Fig. 1 and according to a part of Fig. 5—save for the springs 7 and 17 which are eliminated—it is obvious that when the covers are raised, this will also raise the plates 2 and 22, due to the respective action of said covers upon the links 8 and 18.

In Fig. 9, the distributor comprises a single chamber or space. A vertical sleeve 23 protects the link which connects the cover with the raising parts.

In Fig. 11, the distributor comprises two chambers 24 and 25 of suitable size, each being adapted to contain a package of cigarettes, and it further comprises a middle chamber 26 holding matches which are loosely disposed, as well as a recess 27 for the functioning of the link actuating the rising plate 20 which is disposed below the said chambers.

Obviously, the forms and the accessory dispositions of the several parts of the apparatus hereinbefore described, as well as the dimensions, material, means and details of construction, such as the number and dis-

position of the said chambers, may be varied without departing from the spirit of the invention.

Having thus described my invention, what I claim is:

1. In a dispensing receptacle of the type described, the combination of a casing, a hinged cover for said casing, a horizontally disposed guide member in said casing having a plurality of vertically extending article guiding passages formed therein, a lifting plate slidably mounted in said casing beneath said guide member, a lever pivoted to the bottom of said casing and slidably engaging said plate and a link pivotally connecting said lever to said cover for the purpose described. 70

2. In a dispensing receptacle of the type described, the combination of a casing, a hinged cover for said casing, a horizontally disposed guide member in said casing having a plurality of vertically extending article guiding passages formed therein, a lifting plate slidably mounted in said casing beneath said guide member, a lever pivoted to the bottom of said casing having an elongated ar- 75 80

cuate slot therein, a bifurcated bracket on said plate engaging said lever, a pin carried by said bracket lodged in said slot and a link pivotally connecting said lever to said cover for the purpose described. 90 95

3. In a dispensing receptacle of the type described, the combination of a casing, a hinged cover for said casing, a horizontally disposed guide member in said casing having a plurality of vertically extending article 100

guiding passages formed therein, a lifting plate slidably mounted in said casing beneath said guide member, a lever pivoted to the bottom of said casing and slidably engaging said plate, a link pivotally connecting said lever to said cover, spring means tending to turn said lever in the direction of said plate and releasable means for securing said cover in closed position for the purpose described. 105

4. In a dispensing receptacle of the type described, the combination of a casing, a hinged cover for said casing, a horizontally disposed guide member in said casing having a plurality of vertically extending article 110

guiding passages formed therein, a lifting plate slidably mounted in said casing beneath said guide member, a lever pivoted to the bottom of said casing having an elongated ar- 115 120

a plurality of vertically extending article guiding passages formed therein, a lifting plate slidably mounted in said casing beneath said guide member, a lever pivoted to the bottom of said casing and slidably engaging said plate, a link pivotally connecting said lever to said cover, a second casing mounted on said lifting plate and extending through said guide member, a hinged cover for said second casing, a horizontally disposed guide member in said second casing having a plurality of vertically extending article guiding passages formed therein, a lifting plate slidably mounted in said second casing beneath said second guide member, a vertically disposed guide rod for said second lifting plate, a collar on said second lifting plate slidably engaging said guide rod and a link pivotally connecting said collar and the cover of said second casing for the purpose described.

6. In a dispensing receptacle of the type described, the combination of a casing, a hinged cover for said casing, a horizontally disposed guide member in said casing having a plurality of vertically extending article guiding passages formed therein, a lifting plate slidably mounted in said casing beneath said guide member, a lever pivoted to the bottom of said casing having an elongated arcuate slot therein, a bifurcated bracket on said plate engaging said lever, a pin carried by said bracket lodged in said slot, a link pivotally connecting said lever to said cover, a second casing mounted on said lifting plate and extending through said guide member, a hinged cover for said second casing, a horizontally disposed guide member in said second casing having a plurality of vertically extending article guiding passages formed therein, a lifting plate slidably mounted in said second casing beneath said second guide member, a vertically disposed guide rod for said second lifting plate, a collar on said second lifting plate slidably engaging said guide rod and a link pivotally connecting said collar and the cover of said second casing for the purpose described.

7. In a dispensing receptacle of the type described, the combination of a casing, a hinged cover for said casing, a horizontally disposed guide member in said casing having a plurality of vertically extending article guiding passages formed therein, a lifting plate slidably mounted in said casing beneath said guide member, a vertically disposed guide rod for said lifting plate, a collar on said lifting plate slidably engaging said guide rod, a link pivotally connecting said collar and said cover, a coil spring disposed on said guide rod and abutting the said collar and the bottom of said casing and releasable means for securing said cover in closed position for the purpose described.

In testimony whereof I affix my signature.
